PHOTO-INDEX CATHODE RAY DEVICE

Francis P. Keiper, Jr., Oreland, Pa., assignor to Philco Corporation, Philadelphia, Pa., a corporation of Pennsylvania

Filed Dec. 17, 1958, Ser. No. 781,106

9 Claims. (Cl. 250—217)

This invention relates to photo-index type cathode ray devices in which indexing signals are produced by electron beam impingement of light-emissive indexing elements and by translation of the emitted light into electrical signals. Such a device is useful, for example, as the display device of a color television receiver, in which case the indexing signals are utilized to ensure proper color rendition. In the preferred form of such a display device, the color image-producing elements are in the form of phosphor stripes extending transversely to the direction of line scanning, the stripes being arranged in successive groups whose individual stripes emit light of different primary colors, and the indexing elements are in the form of stripes parallel to the image-producing stripes.

In the preferred form of such a device, the light which produces the indexing signals is emitted rearwardly from the cathode ray tube screen within the funnel or bell portion of the tube envelope and is collected by a photoelectric device suitably arranged to receive the light.

An improved form of such a cathode ray device is disclosed in U.S. Patent No. 2,749,449, issued June 5, 1956, to W. E. Bradley et al., which teaches the provision of a light reflecting and diffusing surface on the inside of the bell portion of the cathode ray tube to serve as a light funnel for directing light to a photoelectric collecting device contained within an opaque envelope or housing adjacent the outside of a window in said bell portion. The provision of the light reflecting and diffusing surface on the inside of said bell portion increases the amount of light received by the photoelectric device and thus increases the amplitude of the indexing signals.

While the structure taught in the Bradley et al. patent represents an important advance in the art, in practice it has been found that there is still room for improvement in respect to the amplitude of the indexing signals in order to assure proper drive of the correction control circuits. Although the light reflecting and diffusing surface of the Bradley et al. patent causes far less light loss than does a light-absorbing coating, such as the previously used aquadag coating, only a relatively small portion of the light reaches the photoelectric device. This is due to the fact that the area of the photocathode, which is in confronting relation to the aforementioned window, is small in relation to the area of the light reflecting and diffusing surface.

Having in mind that the objective is to deliver as much light as possible to the photocathode of a photoelectric device such as a photomultiplier tube, the amount of delivered light could be increased by increasing the area of the normally planar photocathode. However, this is impractical because it necessitates special construction of the photoelectric device and involves substantial additional cost.

The principal object of the present invention is to provide a highly satisfactory and practical solution of the problem of delivering an adequate amount of light to the photoelectric device.

In accordance with the present invention, there is provided a photo-index cathode ray device employing the light reflecting and diffusing coating of the Bradley et al. patent and also employing an improved light-collection arrangement. The latter comprises a window in the bell portion of the cathode ray tube, an envelope or housing adjacent the outside of said window and having a light reflecting and diffusing surface on the inside thereof, and a photoelectric device having a photocathode within said housing in confronting relation to the light reflecting and diffusing surface of said housing to receive light therefrom. By virtue of this novel structure, the light delivered to the photocathode surface is greatly increased and is fully adequate to assure sufficient amplitude of the indexing signals produced by the photoelectric device.

The invention may be fully understood from the following detailed description with reference to the accompanying drawing wherein the single figure is a longitudinal sectional view of a cathode ray device, for use as the display device of a color television receiver, embodying one form of the present invention.

Referring more particularly to the drawing, there is shown a cathode ray tube 10 of the character disclosed in the aforementioned Bradley et al. patent. The tube comprises the usual neck and bell portions 11 and 12, and the usual faceplate 13. On the faceplate there are color triplets, each comprising phosphor stripes 14, 15 and 16 extending transversely to the direction of line scanning and emissive of light in different primary colors. Placed over the colored light-emissive stripes is an electron-permeable light-opaque film 17 which is preferably formed of aluminum. The screen thus constituted has on its rear surface light-emissive indexing stripes 18 which may be composed of phosphor and which also extend transversely to the direction of line scanning. It will be understood that the stripes 14 to 16 and 18 are not drawn to scale but are merely representative of the screen structure in which the stripes are so multitudinous and so fine as to preclude their being drawn to scale.

On the inside surface of the bell portion 12, there is provided the reflecting and diffusing surface 19 according to the teaching of the Bradley et al. patent. As there described, this surface may be provided by an electrically conductive coating such as a roughened coating of aluminum or silver, in which case the coating may also serve as an anode coating, or the coating may be a non-conductive coating deposited upon the anode, such as might be provided by magnesium oxide crystals. Electrical connection is made to the anode coating through the exterior connector fitting 20.

It will be understood, of course, that the cathode ray tube also comprises the conventional beam producing and focussing elements with which the present invention is not concerned and which therefore are not shown.

For collection of the light emitted by the indexing elements 18, a window 21 is provided in the bell portion 12 of the cathode ray tube. Because of the structure provided by this invention it is possible, and in fact desirable, to employ a clear glass window which may simply comprise a clear portion of the glass wall 12. The window receives light from the elements 18 both directly and by the diffuse reflection of coating 19.

In accordance with the present invention, an envelope or housing 22 is provided, adjacent the outside of window 21, having a light-reflecting and diffusing surface 23 on the inside thereof. This housing may be composed of glass, and the surface 23 may be provided by a coating of the same character as that which provides the surface 19. Thus it will be seen that the surface 23 is effectively an extension of the surface 19 external to the envelope

of the cathode ray tube. Further, in accordance with this invention, a photoelectric device 24 is provided having a photocathode 25 within the housing 22 in confronting relation to the light reflecting and diffusing surface 23.

The device 24 may be a conventional head-on photomultiplier tube having its photocathode extended over a portion of its cylindrical wall. As is well known, the conventional head-on photomultiplier comprises a cylindrical glass envelope having an end wall upon which the photocathode surface is provided, an anode within the envelope, and a plurality of dynode electrodes also within the envelope. Such a tube may be adapted for the purpose of the present invention simply by extending the photocathode along a portion of the cylindrical glass wall.

In such case it will be seen that the photocathode comprises two areas, i.e. the end area in confronting relation to the window 21 and the side area in confronting relation to surface 23. However, if the length of the side area is at least equal to the diameter of the end area, the side area is at least four times as large as the end area. Therefore the side area, in cooperation with surface 23, is much more effective than is the end area, and therein resides the improvement provided by this invention. Moreover the combination of the two has the advantage that the effect of the end area is added to that of the side area.

As shown in the drawing, the photomultiplier tube may extend through an opening in the housing 22. The latter is preferably of hemispherical form, although it may be of any other suitable form.

Alternatively, the photoelectric device may be a photodiode having its photocathode extended over its glass surface.

From the foregoing description, it will be seen that this invention represents an advance in the art beyond the contribution of the aforementioned Bradley et al. patent. Thus this invention has provided a novel structural combination including the reflecting and diffusing surface 19 and the collector arrangement in cooperative association therewith.

While a preferred embodiment of the invention has been illustrated and described, it will be apparent that various modifications thereof are possible without departing from the spirit and scope of the invention. It will be understood therefore that the invention is not limited to the illustrated embodiment but contemplates such modifications and further embodiments as may occur to those skilled in the art.

I claim:

1. A photo-index cathode ray device, comprising a cathode ray tube having an envelope including a bell portion and a screen at the larger end of said bell portion, electron-excitable light-emissive indexing elements on the inside of said screen, a light reflecting and diffusing surface on the inside of said bell portion, a light-transmissive window in said bell portion to receive light from said elements both directly and indirectly by the diffuse reflection of said surface, a housing adjacent the outside of said window to receive light transmitted therethrough, a light reflecting and diffusing surface on the inside wall of said housing, and a photoelectric device having a photocathode within said housing in confronting relation to the last-mentioned surface, whereby said photocathode receives light transmitted through said window by the diffuse reflection of the last-mentioned surface.

2. A photo-index cathode ray device according to claim 1, wherein said housing is substantially of hemispherical form.

3. A photo-index cathode ray device, comprising a cathode ray tube having an envelope including a bell portion and a screen at the larger end of said bell portion, electron-excitable light-emissive indexing elements on the inside of said screen, a light reflecting and diffusing sur-

face on the inside of said bell portion, a light-transmissive window in said bell portion to receive light from said elements both directly and indirectly by the diffuse reflection of said surface, a housing adjacent the outside of said window to receive light transmitted therethrough, a light reflecting and diffusing surface on the inside wall of said housing, and a photoelectric device having a photocathode within said housing in confronting relation both to said window and to the last-mentioned surface, whereby said photocathode receives light transmitted through said window both directly and indirectly by the diffuse reflection of the last-mentioned surface.

4. A photo-index cathode ray device according to claim 3, wherein said photo electrode device is of cylindrical form, and said photocathode extends over an end surface and at least a portion of the cylindrical wall.

5. A color television display device, comprising a cathode ray tube having an envelope including a bell portion and a screen at the larger end of said bell portion, said screen comprising both forwardly and rearwardly-presented light-generating elements separated by a thin electron-transparent light-opaque layer, a light reflecting and diffusing surface on the inside of said bell portion, a light-transmissive window in said bell portion to receive light from the rearwardly-presented elements both directly and by the diffuse reflection of said surface, a housing adjacent the outside of said window to receive light transmitted therethrough, a light reflecting and diffusing surface on the inside wall of said housing, and a photoelectric device having a photocathode within said housing in confronting relation to the last-mentioned surface, whereby said photocathode receives light transmitted through said window indirectly by the diffuse reflection of the last-mentioned surface.

6. A color television display device according to claim 5, wherein said housing is substantially of hemispherical form.

7. A color television display device, comprising a cathode ray tube having an envelope including a bell portion and a screen at the larger end of said bell portion, said screen comprising both forwardly and rearwardly-presented light-generating elements separated by a thin electron-transparent light-opaque layer, a light reflecting and diffusing surface on the inside of said bell portion, a light-transmissive window in said bell portion to receive light from the rearwardly-presented elements both directly and by the diffuse reflection of said surface, a housing adjacent the outside of said window to receive light transmitted therethrough, a light reflecting and diffusing surface on the inside wall of said housing, and a photoelectric device having a photocathode within said housing in confronting relation both to said window and to the last-mentioned surface, whereby said photocathode receives light transmitted through said window both directly and indirectly by the diffuse reflection of the last-mentioned surface.

8. A color television display device according to claim 7, wherein said photoelectric device is of cylindrical form, and said photocathode extends over an end surface and at least a portion of the cylindrical wall.

9. A color television display device according to claim 8, wherein the length of the photocathode area on said cylindrical wall is at least equal to the diameter of said end surface, whereby the photocathode area on said cylindrical surface is at least four times as large as the photocathode area on said end surface.
